UNITED STATES PATENT OFFICE.

GEORGE F. STEINKAMP, OF CINCINNATI, OHIO.

BATH FIXTURE.

Application filed September 30, 1922. Serial No. 591,468.

To all whom it may concern:

Be it known that I, GEORGE F. STEINKAMP, a citizen of the United States of America, and a resident of Cincinnati, in the county 5 of Hamilton and State of Ohio, have invented a certain new and useful Improvement in Bath Fixtures, of which the following is a specification.

This invention has relation to improvements in bath-fixtures used in bathing the 10 human body, and, more especially, to those combining in their structure a wash-stand feature.

The details of the structure and its advantages will be fully hereinafter described 15 in connection with the accompanying two sheets of drawings, in which—

Figure 1 is a quasi-perspective view of my invention, taking it as it appears ordinarily 20 in use in a contracted space that serves to accomplish the great or important feature of my device, including pool, seat, valves and spray or shower, but not showing the minute details of structure of said valves and 25 shower; Fig. 2, a fragmentary transverse section of the pool and seat elements, including broken-off parts of the side-walls of the bath-chamber; Fig. 3, a perspective view of the pool-member, the seat, the side-plates and 30 the shallow water-guard, all being made integral and constituting the main elements of the invention herein, but omitting the water-control valve and shower elements; Fig. 4, a front-to-rear cross-section of the 35 bathing-pool, seat, valve, shower and back-wall elements, showing the proper angle of shower-delivery and the fore supporting-legs; Fig. 5, a fragmentary front-to-rear section of the left-hand fore end of the bathing- 40 pool member showing its adjustable supporting means for suitably leveling the device in setting it up for use, and more especially for wash-stand purposes; and Fig. 6, a detached perspective of the adjusting block 45 and its screw-shank seen in Fig. 5.

9 indicates the main-plate forming the seat for the bather and arranged to the immediate rear of the water chamber or pool 10 that is shorter at its opposite ends than the 50 said seat to make due provision for the horizontal side-plates 11 and 12 that are both on a level that is slightly below that of the seat.

The side-plate 11 has a series of three ori- 55 fices or openings *d*, *e* and *f* made therein for the special purposes hereinafter referred to.

13 indicates a downwardly-turned water guard or rounded apron provided along the front of the water chamber or pool 10, and arranged at a level a little higher than that 60 of the side-plates 11 and 12, but at a somewhat lower level than that of the seat 9, as best shown in Fig. 4.

A water skirting or guard, composed of the upright side-members 14, 14 and a rear-member 15, extends from the said front guard or apron 13 to the rear of the main-plate or seat 9, at a suitable elevation above the side-plates 11 and 12 and, also, that of the seat 9, and it has a horizontal top surface 14^a on which the hard cement wall 16 is built, such cement wall being laid on the face of the ordinary plastered wall 17 of the vertical walls A, B and C of the contracted compartment in which it is preferably, but not essentially, designed to inclose my improved bathing-fixture for its use.

The rear wall 18 of the bathing-pool 10 has an overflow orifice or opening 20 and the bottom of the pool is provided with a discharge orifice or opening 21 adapted to the use of the ordinary plug (not shown). 19 is the front wall of the pool or basin 10. A door, or drapery, (not shown) is adapted to be placed in the opening between the outer 80 edges of the vertical side-walls A and C of the said contracted compartment in which my device is installed for use.

The bottom of the seat-skirting 15 of the main-plate 9 is downwardly-turned into 90 hook-form, as shown at 22, to engage an up-turned flange 23 provided along the upper edge of a horizontal bar 24 that is secured by means of screws or the like 25 upon the rear wall B of the said contracted compartment, as best shown in Fig. 4, for firmly supporting the inner end of my fixture in place in the said compartment.

26 indicates each one of a pair of vertical legs used at the fore or outer end of my fixture to support it just back of the apron or front-guard 13, as best seen in Fig. 5.

Rectangular sockets 27 are provided in the underside of the side-plates 11 and 12, just forward of a transverse line with the orifice *d* in side-plate 11 therein, for the engagement of the elongated rectangular blocks 28 that surmount the screw-threaded shanks 29, the latter, in turn, engaging threaded bores or openings made in the 105 otherwise-closed tops or upper ends 30 of the vertical hollow legs 26 and adapted to

be elevated or lowered to adjust the height of the fixture above the floor for the desired level in due relation to the rear fastening devices above described, as well as to meet 5 the desired height at which the fixture is to be supported above the floor so that it may also be used as a wash-stand with convenience and comfort.

The passage-way 31 is provided in the rear 10 wall 18 of the bathing-pool 10 to lead from the overflow-orifice 20 into the discharge-orifice 21 in the bottom of the said pool.

A spray or shower device is added to the bathing-pool and seat members of my fixture 15 herein and is composed of an adjustably-mounted rose 32 at the inner end of a short horizontal nozzle pipe or tubing 33, the latter being an angular extension of an upright water pipe 34 and a lower horizontal water- 20 inlet pipe 35. The water-supply control, which is not specifically claimed herein, may be properly termed a triple faucet device, or one having a cold-water inlet-valve D, a hot-water inlet-valve E and a duplex pool and 25 shower control and reverse valve F, the shell of the latter having a spout 50 that discharges into the basin 10.

When it is desired to use the shower or spray device, both of the valves D and E are 30 opened to suit the temperature required. The tempered water is then free to pass through the horizontal pipe 35, the vertical pipe 34, the short horizontal nozzle-pipe 33 and the rose-sprayer 32, thence at the desired 35 angle, or approximately that of the diverging dotted-lines seen in Fig. 4, which directs the shooting drops of water on the back and head of the seated person on the main-plate or bather's seat 9. While, or after bathing, 40 to let the water run cooler than in its prior mixed or tempered condition, or to let it run entirely cold, as desired, all that is necessary is to regulate the hot-water valve sufficient to decrease its delivery or flow for the cooler 45 stage, or close it altogether for the said entirely cold stage.

The bather, when seated in the fixture with his feet in the basin and having the faucet device within easy reach, can, at will, by simply turning the central control-handle F, direct the onward flow of water to the shower or to the basin without changing the temperature of the already properly tempered water, thereby avoiding all danger of scalding himself with hot water. The 50 desired mixture of water should, as a matter of course and precaution, be secured before the bather enters the fixture.

I claim:—

1. In a bathing-fixture, the combination 60 of a large horizontal plate or bathing-seat proper, a sunken basin or pool arranged below the upper level and in front of the said seat-proper, a pair of sunken horizontal side-plates for the basin also arranged below 65 the level of the seat-proper, a side and rear upright water-guard extending above the level of the seat-proper and having a horizontal top edging or surface on which the wall-facing of cement or the like is built, 70 means for supporting the fixture, and an apron or downwardly-turned front-plate for the said basin extending above the level of the said side-plates but below that of the 75 said seat-proper and having a rounded upper edge, substantially as shown and described.

2. In a bathing-fixture, the combination 80 of a seat-proper, a basin arranged forward of and below the level of that of the said seat-proper, horizontal side-plates arranged forward of and below the level of that of said seat-proper, an elevated water-guard provided along the side and rear edges of the said seat-proper, a down-turned apron 85 provided along the front of the said basin below the level of that of said seat-proper, and water supply and controlling means for the fixture, substantially as shown and described.

GEORGE F. STEINKAMP.
